CIRCUIT BREAKER

John W. May, Pittsburgh, and Ture Lindstrom, Edgewood, Pa., assignors to Westinghouse Electric & Manufacturing Company, East Pittsburgh, Pa., a corporation of Pennsylvania

Application October 21, 1941, Serial No. 415,924

18 Claims. (Cl. 200—88)

This invention relates to circuit interrupters, and more particularly to circuit breakers of the type which are automatically operated in response to overload currents in the circuit controlled by the breaker.

One object of the invention is to provide a circuit breaker with an improved device of simple and inexpensive construction, which is operable to cause the breaker to automatically open its contacts in response to overloads in the circuits.

Another object of the invention is the provision of an improved circuit breaker which is capable of being tripped by the application of a relatively light tripping force by the electro-responsive trip means.

Another object of the invention is the provision of a circuit breaker having a novel trip device comprising a spring means in which energy is stored by the closing movement of the breaker and which is released by a latch to cause automatic opening of the breaker mechanism in response to predetermined overload conditions in the circuit.

Another object of the invention is the provision of a circuit breaker having a novel tripping means comprising a spring means connected between a tripping element and a part movable with the movable contact assembly, the tripping element being normally held in inoperative position by a latch which is adapted to be released in response to abnormal current conditions in the circuit.

Another object of the invention is the provision of a circuit breaker as previously described wherein the opening movement of the breaker acts through the tripping spring to reset the tripping element to latched position.

Another object of the invention is the provision of a circuit breaker as previously described wherein the spring means for tripping the breaker and for resetting the trip device also serves to permit overtravel of the parts to which the spring is connected in both directions of operation.

Another object of the invention is to provide a circuit breaker having an improved trip mechanism which is reset automatically when the contacts are opened.

Another object of the invention is to provide a circuit breaker wherein the movement of the operating mechanism to open the contacts resets the trip device.

Another object of the invention is to provide a circuit breaker with a novel spring device which is normally under tension to effect tripping

of the breaker, and which is operable upon opening of the contacts to reset the trip device.

A further object of the invention is to provide a circuit breaker with an improved mechanism operable when tripped in response to overload currents to trip the breaker and operable upon operation of the breaker to reset the trip device.

Still another object of the invention is to provide a circuit breaker with a novel linkage operable in one direction to trip the breaker and operable in another direction to reset the trip device.

The novel features that are considered characteristic of the invention are set forth in particular in the appended claims. The invention itself, however, both as to structure and operation, together with additional objects and advantages thereof, will be best understood from the following description of one embodiment thereof when read in conjunction with the accompanying drawings, in which:

Figure 1 is a vertical sectional view through the center pole of a three-pole circuit breaker embodying the features of the invention;

Fig. 2 is a horizontal sectional view on an enlarged scale taken substantially on line II—II of Fig. 1, and showing the trip device of the breaker;

Fig. 3 is a fragmentary view showing the contact arm for the outer poles of the breaker;

Fig. 4 is an enlarged sectional view through the trip device for the center pole taken substantially on line IV—IV of Fig. 2, and showing the trip device just after the breaker has been tripped by the bimetal trip element, but before the contacts have opened;

Fig. 5 is an enlarged sectional view similar to Fig. 4, but showing the parts of the trip mechanism in the positions assumed after the breaker has been tripped by the bimetal trip element and after the contact arm has moved to open the contacts, but before the bimetal trip element has cooled;

Fig. 6 is an enlarged sectional view through the resilient linkage connecting the trip lever to the contact arm; and

Fig. 7 is a fragmentary view, partly in section, taken on line VII—VII of Fig. 4, showing the construction of a part of the trip device.

Referring particularly to Figs. 1 and 2 of the drawings, the circuit breaker, which is of the multi-pole type, is mounted on a base 11 of molded insulating material. Secured to the base 11 is a frame structure comprising a pair of

substantially parallel side frames 17 rigidly connected adjacent the base 11 by a cross-frame 19, whereby the frame structure is secured to the central part of the base 11 through the agency of bolts 21 and 23. The side frames 17 are joined at their outer ends by cross-members 25 and 26 to form a rigid framework. The breaker mechanism may be enclosed in a casing, indicated by dot and dash lines at 13, which may be suitably secured to the base 11.

A contact arm 30 for the center pole of the breaker is provided with a pair of spaced arms 31 pivotally mounted on a rod 29 supported by the side frames 17 (see also Fig. 2). The arms 31 are rigidly connected by a cross-bar 32 adjacent the pivot 29. At its free end, the contact arm 30 for the center pole is provided with spaced projections 33, and a movable contact member 35 is pivotally mounted on a pivot pin 37 supported in the projections 33.

A movable contact 39 secured on the contact member 35 cooperates with a stationary contact 40 mounted on a conductor 41 secured to the base 11 by bolts 43. The conductor 41 is bent at right angles and projects through the base 11 where it forms a terminal 45.

Contact pressure is provided by a spring 63 surrounding a rod 61 pivotally connected to the contact member 35. The rod 61 slidably projects through an opening in a projection 59 on the contact arm 30, and the spring 63 is compressed between this projection and a washer 65 secured to the rod 61.

The circuit breaker of the instant invention is of the multi-pole type, and each pole is provided with a stationary contact and a corresponding movable contact similar to the contacts of the center pole. However, only the center pole is provided with a contact arm 30 supported by pivoted arms 31. A tie-bar 67 surrounded by a sheath 69 of insulating material is securely clamped in the arm 30 by means of a split clamp 70 and a bolt 71. The tie-bar 67 extends across all of the poles of the breaker, and has brackets 73 (Fig. 3) clamped thereon by means of a clamp 77 and a bolt 78, there being a bracket 73 associated with each of the outer poles of the breaker. The insulating sheath 69 between the tie-bar and the clamps 70 and 77 insulates the three movable contacts 35 from the tie-bar. Each of the brackets 73 for the outer poles is provided with spaced projections 33 which pivotally support a contact member 35. This contact member is the same as the contact member described in connection with the description of the contacts for the center pole, and like parts have been given the same reference characters. The contact members 35 for the outer poles are pivoted on pivot pins 37 and are provided with contact pressure springs 63. The stationary contact and terminal for each of the outer poles is identical to that of the center pole previously described.

Since the brackets 73 which carry the outer contact members 35 are mounted on the tie-bar 67, which is securely clamped in the contact arm 30 (Fig. 1) for the center pole, it is clear that operation of the contact arm 30 will simultaneously operate the contacts for all of the poles of the breaker.

When the contact arm 30 is rotated clockwise to open the contacts, the springs 63 cause the contact members 35 to rotate in a counter-clockwise direction about their pivot pins 37 so that only the tip portions of the movable contacts

engage the stationary contact members 41 prior to separation of the contacts. Continued clockwise movement of the contact arm 30 causes nuts 75 on the rods 61 to strike the projections 59 and thus limit the movement of the contact members 35 relative to the contact arm 30, and the three movable contacts are then moved to open position with the contact arm 30.

The arc incident to the rupture of the circuit is extinguished by an arc extinguisher 76, one being provided for each pole. Such arc extinguishers are well known in the art and comprise, generally, a stack of slotted plates disposed adjacent the path of movement of each contact member 35. The plates of the extinguisher draw the arc toward the ends of the slots, which results in breaking up the arc into a plurality of short arcs and causes said arcs to be cooled and extinguished.

The electrical circuits for the several poles of the breaker are essentially the same, each circuit extending from the terminal 45 through the conductor 41, contacts 40 and 39, the contact member 35, a flexible shunt conductor 79, a connector 27 of conducting material, a conductor 81, a connector 49 to which one end of the conductor 81 is secured by a screw 51, to a terminal conductor 53 secured to the base 11 by a pair of bolts 55, one of which serves to secure the connector 49 to the conductor 53. The conducting member 27 of the center pole is secured to the cross piece 19 of the frame by the bolt 23, and the conducting members 27 of the outer poles are bolted to the base 11 with a spacer between the base and each member to align the outer conducting members 27 with the corresponding element 27 of the center pole. The terminals 45 and 53 of each pole serve to connect the breaker in an electrical circuit.

The contact arm 30, together with the tie-bar 67, is biased in a clockwise direction toward open contact position by a pair of springs 85 (only one being shown) having one end anchored on a fixed pivot 87 in the frames 17, and the other end connected to a projection 88 on the arm 30. In the closed position of the breaker, the contact arm 30 is releasably restrained in closed contact position (Fig. 1) by means of a linkage and toggle mechanism, including a lever 89 comprising a pair of levers rigidly connected by a cross-member 117 and pivotally supported on a pivot 91 mounted on the main frame 17. A main operating toggle comprising links 93 and 95 operatively connects the lever 89 and the contact arm 30. The link 93 is pivoted on a pivot 101 in the lever 89, and the toggle links 93 and 95 are pivotally connected by a knee pin 97. The link 95 is pivoted on a pivot pin 99 supported between the arms 31 of the contact arm 30. The link 95 comprises a pair of links joined by a cross-bar 115, which cooperates with an extension of the link 93 to limit upward movement of the main operating toggle.

A link 103 connects the lever 89 to one arm of a lever 105 pivoted on the fixed pivot 87. The other arm of the lever 105 is pivotally connected to one end of a toggle link 107 having its other end pivoted to a toggle link 109 by a knee pin 111. The toggle link 109 is pivoted on a fixed pivot 113 supported in the frame 17. The link 107 comprises a pair of links rigidly connected by a yoke 119, which is provided with a projection bent outwardly therefrom, to which projection is secured an extension 121. The purpose 75 of the extension 121 is to cooperate with man-

ually operable means to trip the breaker, as will be described later. The link 103 and the lever 105 each comprises a pair of parallel members joined by a yoke substantially as illustrated. The toggle link 109 comprises a pair of links rigidly connected at their ends adjacent the fixed pivot 113 by a cross-member 123 having formed projections 124 and 127 thereon.

The linkage just described serves to releasably hold the contact arm and consequently the contacts in the closed position. In the closed position, the main operating toggle 93-95 is over center above a line connecting the centers of the pins 99 and 101, the overcenter position of the toggle being limited by the end of the link 93 engaging the cross-member 115 on the link 95. With the toggle 93-95 in its overcenter position, the force exerted by the springs 85, acting through the contact arm 30 and the toggle 93-95, biases the lever 89 in a clockwise direction. The tripping toggle 107-109 is biased over center to the left of a line drawn through the center of the fixed pivot 113 and the point of connection of the link 107 with the lever 105, by a spring 128 tensioned between the yoke 119 and the fixed pivot 113. The overcenter movement of the toggle 107-109 is limited by the projection 124 striking an adjustable screw 122 in the cross-member 25 of the frame. The toggle 107-109 in its overcenter position, acting through the lever 105 and link 103, prevents clockwise rotation of the lever 89 and consequently holds the contact arm 30 in its closed contact position.

The tripping toggle 107-109 is adapted to be moved to collapsed position to cause opening of the contacts by a trip device indicated generally at 133 (Figs. 1, 4 and 5) acting through a trip rod 135 slidably mounted in a bracket 138 secured to the frame 17. The trip device, when actuated in response to an overload current, thrusts the rod 135 upwardly. During its upward movement, the rod 135 strikes the formed portion 127 of the cross-member 123 of the tripping toggle link 109, and rocks said link clockwise about its fixed pivot 113, causing collapse of the tripping toggle 107-109 and linkage 89-103-105.

Collapse of the tripping toggle 107-109 permits the springs 85 to rock the contact arm 30 in a clockwise direction to open the contacts. The main operating toggle 93-95 does not immediately collapse, but moves as a unitary linkage to transmit the movement of the contact arm to the lever 89, rocking this lever clockwise, and through the link 103 rocks the lever 105 also in a clockwise direction to complete the collapse of the tripping toggle 107-109.

The clockwise or opening movement of the contact arm 30 is arrested by the tie-bar 67 striking a portion 137 of the frame 17, and at this time due to the momentum of the toggle 93-95, including the comparatively heavy cross-bar 115, the main toggle 93-95 is caused to move over center in a direction to cause its collapse. By the time the knee pin 97 of the main toggle has passed below the center line 99-101, the weight of the linkage and parts causes the main toggle to collapse and causes the lever 89, link 103, lever 105, and the tripping toggle 107-109 to be automatically reset to their normal positions, as shown in Fig. 1.

As soon as the main toggle 93-95 collapses, the effectiveness of the linkage 93, 95, 89, 103 and 105 is destroyed, and the spring 128 aids in restoring the toggle 107-109 to its normal over-

center position and in restoring the lever 105, link 103 and lever 89 to their normal position. The main toggle 93-95 remains in its collapsed condition until the contacts are reclosed.

In order to manually close the contacts, a manually operable handle 141 is provided. This handle is secured on the outer end of a short shaft 142 rotatably supported in a bracket 143 of insulating material. The bracket 143 is secured by screws 144 and 146, respectively, to the cross-members 25 and 26 of the frame 17. The free end of a crank arm 150, secured to the shaft 142 adjacent the bracket 143, is bifurcated and pivotally carries a downwardly extending link 151. The lower end of the link 151 is notched and engages an hourglass-shaped roller 153 rotatably mounted on a cross-bar 147 rigidly connecting the outer ends of a pair of levers 145 pivotally supported on the shaft or fixed pivot 91. Near their inner ends, the levers 145 are rigidly connected by a cross-bar 149. The levers 145 and the cross-bars 147 and 149 form a closing lever pivoted at 91, the levers 145 being spaced apart and disposed on the outside of the frame 17. Projections 152 on the cross-bar 149 have mounted therein a pivot 157, upon which is rotatably mounted a roller 155.

Rotation of the handle 141 in a clockwise or closing direction, indicated by the arrow (Fig. 1), thrusts the link 151 downwardly and, due to the cooperation of the link with the roller 153, rocks the closing lever 145 in a clockwise direction. During this movement, the roller 155 engages the link 93 of the now collapsed toggle 93-95 and moves said toggle to its overcenter position. Since at this time the toggle 107-109 is over center in its restraining position, the lever 89 is prevented from moving. Consequently, the force applied to straighten the toggle 93-95 rotates the contact arm 30 in a counterclockwise direction to close the contacts and tension the springs 85. The clockwise movement of the closing lever 145 and the roller 155 is sufficient to carry the toggle 93-95 over center above the line 99-101, so that the contacts are held in their closed position until the breaker is again tripped.

As soon as the contacts are closed and the toggle 93-95 is moved to its overcenter position, the handle 14 may be released, whereupon a spring 159 tensioned between a projection on the frame 17 and the closing lever 145 rocks the closing lever counterclockwise, thrusting the link 151 upwardly and rotating the handle to its neutral position (Fig. 1). The counterclockwise rotation of the lever 145 is limited by the cross-bar 149 striking a stop 148 in the bracket 138.

The contacts 39-40 may be closed (and the trip device 133 reset) automatically by means of an electric motor 125 mounted on a plate 126 (see Fig. 2) secured to the side of the frame 17. The motor 125 may be energized from any suitable source and in a manner well known in the art, and when so energized it is adapted, through suitable driving connections, to rotate a crank disc 129 which carries an anti-friction roller 130. An arm 131 secured to the side of the closing lever 145 is provided with a cam surface 132 normally disposed in the path of rotation of the roller 130.

When the crank disc 129 is rotated, upon energization of the motor 125, the anti-friction roller 130 engages the cam surface 132 and rotates the arm 131, and consequently the closing lever 145 clockwise, straightening the toggle 93-95, in the manner previously described, to close the con-

tacts. As soon as the roller 130 passes out of engagement with the arm 131, the spring 159 acts to restore the closing lever 145 to its normal, unoperated position (Fig. 1). The motor 125 is deenergized by a suitable limit switch (not shown).

The breaker may be tripped manually by rotating the handle 141 through a small angle in a counterclockwise direction from its neutral position. Rotation of the handle in tripping direction causes a projection 161 (Fig. 1) on the link 161 to engage the previously described extension 121 on the yoke 119 of the toggle link 107, and move the tripping toggle 107—109 over center in a direction to cause its collapse. This permits the springs 85 to open the contacts, as was previously described. Reclosing the contacts is effected in the previously described manner.

The trip device 133 is removably supported on the circuit breaker to provide for interchanging of trip devices having different tripping characteristics. The trip device is mounted on a framework including a U-shaped bracket 163 (Figs. 1, 2, 4 and 5) secured to the center pole connector 21 by means of the screw 28, which secures the conductor 81 thereto. The bracket 163 has a pair of upwardly bent side members 165 (see Fig. 2) and a portion 167 (Fig. 4), to the underside of which portion 167 is secured a plate 169 of insulating material. Mounted on the plate 169 is a frame 171 also of molded insulating material. An angular flange 173 (Fig. 2) molded integral with the frame 171 is secured to the plate 169 by screws 175.

The trip device 133 comprises a thermally responsive bimetal element operable on overloads below a predetermined value, and an electromagnet operable on overloads above the predetermined value, there being one bimetal element and one electromagnet for each of the three poles of the breaker. The conductor 81 previously mentioned extends downwardly from the connector 21, and is bent at right angles and extends to the right (Fig. 5) along the bottom face of the plate 169 for a predetermined distance where it is bent back upon itself. This looped portion of the conductor strip is made of reduced width to provide an increased resistance portion so that it serves as a heater for the bimetal element. Just to the left of the plate 169, the conductor 81 is again bent toward the right and then downwardly to the connector 49.

The upper leg of the loop of the conductor 81 is secured to the plate 169 by a rivet 177 (Figs. 4 and 5), and the reversely bent portion of the loop is secured to a bimetal element 179 and to a bracket 181 (see also Fig. 7). The downwardly extending leg of the conductor 81 passes between the legs of a U-shaped magnet core 183, which, together with the bracket 181, is securely attached to projections 185 and 187 (Fig. 7) of the frame 169 by means of rivets 189. A block 191 of insulating material is inserted between the legs of the loop of the conductor 81 to separate the legs and to form a substantially rigid structure.

Overload currents traversing the circuit of any pole of the breaker, and consequently the conductor 81 of any pole, serve to heat the bimetal 179 of the affected pole and to energize the corresponding magnet core 183.

A movable armature 193 is secured on the end of a rod 195 slidably mounted in an opening in a downwardly extending portion 197 of the bracket 181. A spring 199 compressed between a shoulder on the rod 195 and the bracket

181 maintains the armature 193 in open air gap position (Figs. 1 and 4), and returns the armature to this position from its attracted position. The right-hand end (as viewed in Figs. 1, 4 and 5) of the rod 195 is provided with a head 201 which engages a U-shaped notch molded in a trip bar 203. The trip bar is of molded insulating material, and has a metal member 205 molded therein at each end. The members 205 (only one of which is shown) are pivotally supported on spaced brackets 207 secured to and depending from the plate 169, and serve to pivotally support the trip bar. At their lower ends, the brackets 207 support a cover 209 of insulating material held in place by screws 211. The trip bar 203 is biased to its latching position (Fig. 1) by a spring 213 (Figs. 4 and 5) compressed between a projection 215 of the trip bar and the plate 169.

Only one trip device 133 has been described. However, it is to be understood that a plurality of trip devices are provided, one for each of at least two poles of the breaker, all of which are mounted on the plate 169 substantially as illustrated and described. Each of the trip devices is operable in response to overload conditions in the circuit of their corresponding poles to rotate the trip bar 203 in tripping direction to trip the breaker, the trip bar extending across all of the poles of the breaker.

Attached to the trip bar 203 is a latch member 217 provided with a latch projection 219 and a limit projection 221. The latch member 217 is adapted to engage the end of a latch arm 223 pivotally supported on a short shaft 225 mounted in the side members 165 of the U-shaped bracket 163. The latch arm 223 is provided with a yoke 227, one end of which forms an arm 229 (Fig. 2) bearing on the shaft 225. A spring 231 is coiled about the shaft 225 and disposed to bias the latch arm 223 in a counterclockwise direction (Fig. 1) toward its latched up position.

A pair of locating members 233 is rigidly supported on a rod 235, mounted in the frame 171, and on the shaft 29. Each of the members 233 is provided with a open slot embracing the shaft 225 to aid in locating the trip device 133 when it is installed in the breaker, and to assist in supporting the trip device after it is installed. The members 233 are spaced apart by a spacer 237 surrounding the rod 235 and a spacer 239.

The trip device 133 does not itself operate the trip rod 135 to trip the breaker, but releasably restrains a tripping mechanism, indicated generally at 240 (Fig. 5) in operative position. The tripping mechanism 240, when released upon operation of the trip device 133, operates the trip rod 135 to trip the breaker.

The trip mechanism 240 is mounted on a laterally extending bar 241 molded integral with the frame 171. The bar 241 supports a bracket 243 comprising a pair of parallel side plates 245 rigidly connected by a yoke 247, which yoke is secured to the bar 241 by bolts 249. The upper ends of the plates 245 between them support a pivot shaft 251, upon which is pivotally mounted a lever comprising a pair of arms 253, one of which has a downwardly projecting extension 255 engageable with the yoke 227 of the latch arm 223. The arms 253 are rigidly joined by a yoke 259, and at their free ends carry a pivot pin 261. A pair of links 263 pivoted on the pin 261 are pivotally connected to spaced arms 265 of a bell crank or trip member 267 by means of a pivot pin 269. The bell crank 267 comprises

the spaced arms 265 connected by a yoke 271, the bell crank being pivotally supported on a pivot pin 272 mounted in the lower ends of the spaced plates 245. The other arm 273 of the bell crank 267 is integral with one of the arms 265 and has an ear 275 bent at right angles to its free end. An adjustable screw 277 is mounted in the ear 275, and is locked in position by a lock nut 278.

When the trip mechanism 240 is operated, as will be described later, the bell crank 267 is rocked counterclockwise, and the screw 277 strikes the lower end of the previously described trip rod 135 to effect tripping of the breaker.

The point of connection 281 of the links 253 and 263 is connected to the arms 31 of the contact arm 30 by means of a resilient linkage indicated generally at 281 (Figs. 1, 4, 5 and 6). Referring particularly to Fig. 6, the resilient linkage 281 comprises a cylinder 283 pivotally mounted on a rod 285 which extends through a transverse opening in the cylinder and through suitable openings in the arms 31 of the contact arm 30, a rod 287 pivotally supported on the pin 261, and a compression spring 289 compressed between washers 291 and 293 in the cylinder. The washer 291 is adapted to engage the inner end of a cylindrical sleeve 295 mounted in the cylinder 283 and held in place by the rod 285 passing therethrough. The sleeve 295 acts as a limit stop to limit the expansion of the spring 289; the washer 293 engaging the inwardly flanged end 297 of the cylinder 283 serves the same purpose. A spacer 299 (Fig. 4) surrounding the rod 285 spaces the linkage 281 adjacent one of the arms 31 and maintains it in alignment with the linkage 253-263.

In the normal untripped condition, the flexible linkage 281 is under tension, that is, the rod 287 is slightly drawn out of the cylinder 283, giving a greater compression to the spring 289 than obtains with the parts in the positions shown in Fig. 6. The force of the spring 289 is applied to the pin 261 and biases the lever 253 and the bell crank 267 in a counterclockwise or tripping direction. Movement of the lever 253 and bell crank 267 is normally prevented by engagement of the projection 255 with yoke 227 of the latch arm 223, which is normally latched up by the latch member 219 (see Fig. 1).

Upon the occurrence of a persistent overload current below a predetermined value in the circuit of any one of the poles of the breaker, the current flowing through the corresponding conductor 81 heats the bimetal element 179 and causes it to flex in a downward direction. The free end of the bimetal engages an adjusting screw 301 held in place in the trip bar 203 by a lock nut 303 and rocks the trip bar clockwise to unlatch the latch arm 223. As soon as this occurs, the linkage 281 contracts, due to the expansion of the spring 289 (Fig. 6) within the cylinder 283, rocking the lever 253 counterclockwise. This causes the toggle comprising the lever 253 and link 263 to move further above the center line 251-269, and rocks the bell crank lever 267 counterclockwise to trip the breaker through the agency of the trip rod 135.

The parts just described are shown in Fig. 4 in this position, that is, an instant after the breaker is tripped, but before the contacts have opened.

Operation of the trip rod, as previously described, causes collapse of the linkage 93, 95, 89, 103, 105, 107 and 109 (Fig. 1) which permits

the spring 85 to rotate the contact arm 30 to open the contacts. As the contact arm 30 rotates clockwise in opening direction, the action of the linkage 281 (Fig. 5) is reversed, and the cylinder 283 moves with the contact arm 30, and, acting through the washer 291, the spring 289 and the washer 293, which at this time is in engagement with a shoulder on the rod 287, thrusts the rod 287 in a direction to straighten the toggle 253-263. This simultaneously accomplishes two things. Acting through the link 263, the bell crank lever or trip member 267 is rocked clockwise to its normal position to permit restoration of the trip rod to its normal position, which permits resetting of the linkage 89, 103, 105, 107 and 109 (Fig. 1). The straightening of the toggle 253-263 also rocks the lever 253 clockwise, whereupon the spring 231 rotates the latch arm 223 counterclockwise slightly beyond latching position, this movement of the arm 223 being limited by a projection 305 on the bracket 163.

As the bimetal 179 cools and resumes its normal shape (Fig. 1), the spring 213 rotates the trip bar 203 counterclockwise to latching position with the projecting latch 219 in the path of clockwise movement of the latch arm 223. The counterclockwise movement of the trip bar 203 is limited by the projection 221 thereon striking the arcuate end of the latch arm 223.

Now when the contact arm 30 is rotated in a counterclockwise or closing direction, upon proper operation of the handle 141, or energization of the motor 125, to close the contacts, the linkage 281 moves therewith, rocking the lever 253 counterclockwise a slight amount and through the projection 255 rocks the latch arm 223 clockwise a slight amount until it is arrested by engagement with the latch 219 thus restraining the latch arm and the toggle 253-263 in latched position. This also arrests the counterclockwise movement of the lever 253. Continued closing movement of the contact arm 30 again places the linkage 281 in tension, i.e., stores energy in the spring 289, in readiness for a succeeding tripping operation.

The circuit breaker is tripped instantaneously on overloads in the circuit through any of the poles exceeding a predetermined value; for instance, exceeding approximately ten times normal rated current. Upon the occurrence of an overload above the predetermined value, or a short-circuit, the current flowing through the corresponding conductor 81 energizes the magnet core 183, which immediately attracts the armature 193. The armature draws the rod 195 toward the left (Fig. 5), the head 201 of said rod acting to rock the trip bar 203 in unlatching direction. When the trip bar 203 has unlatched the latch arm 223, the parts function to trip the breaker in the previously described manner. As soon as the contacts are opened and the circuit ruptured, the spring 199 returns the armature 193 and rod 195 to unattracted position, and the spring 213 rocks the trip bar 203 to latching position. The trip mechanism is rest upon movement of the contact arm 30 to open position, and the contacts reclosed as previously described.

The breaker is trip-free under all conditions. Should the handle 141 be held in its closed position against an overload current, holding the roller 155 against the toggle link 93, the contacts will open, since collapse of the linkage 89, 103, 105 and 107-109 permits the toggle 93-95 to move in opening direction as a unitary linkage. When the clockwise movement of the contact arm

30 is arrested by the frame 17, the force of the spring 85 is no longer applied to the toggle 93-95, and the linkage, consequently when the handle 141 is released and the closing lever 145 rotated to normal position, the weight of the linkage acts to move the toggle 93-95 over center to collapsed position and reset the linkage 89, 103, 105 and 107-109. The contacts may now be closed in the previously described manner.

From the foregoing description it will be seen that the parts are so arranged that a very light load is applied to the latch member and therefore requires the application of a relatively light force by the current responsive trip device to unlatch the trip mechanism, the actual work of tripping the breaker mechanism being performed by the spring link. A further advantage resides in the provision of the resilient connection or linkage which operates in one direction to trip the breaker and is operable in another direction, upon opening of the contacts, to automatically restore the latch member to latching position without the necessity of preliminary manipulation of the closing mechanism. The resilient connection also permits operation of the mechanism without strain or breakage since it permits overtravel of the parts in both directions.

Having described the preferred embodiment of the invention in accordance with the patent statutes, it is to be understood that various changes and modifications may be made in the structural details disclosed without departing from some of the essential features of the invention. It is, therefore, desired that the language of the appended claims be given as reasonably broad interpretation as the prior art permits.

We claim as our invention:

1. In a circuit breaker, relatively movable contacts, operating mechanism for said contacts including closing means for closing said contacts, means operatively relating said closing means and said movable contacts, a trip mechanism including a toggle independent of said relating means, said toggle being biased in a direction to cause opening of the contacts, latch means for releasably restraining the trip mechanism, and a current-responsive trip device operable in response to overload circuit conditions to cause said latch to release the toggle and permit operation of the trip mechanism, said toggle being operable by the operating mechanism when the contacts are opened to permit relatching of the latch means.

2. In a circuit breaker, relatively movable contacts, operating mechanism for said contacts, a normally latched trip mechanism having a linkage including a compression spring biased to cause opening of the contacts, a current-responsive trip device operable to unlatch the trip mechanism, said operating mechanism acting through said linkage to reset the trip mechanism when said operating mechanism moves to open the contacts.

3. In a circuit breaker, relatively movable contacts, operating mechanism operable to open and close the contacts, a releasable trip member operable to cause opening of the contacts, a linkage including a compression spring biasing said trip member in tripping direction, and a current-responsive trip device operable in response to overload circuits to release the trip member, said operating mechanism acting through said linkage upon opening of the contacts to cause resetting of parts of said current-responsive trip device.

4. In a circuit breaker, relatively movable contacts, operating mechanism for said contacts, a trip mechanism including a toggle operable to effect opening of the contacts, a spring means biasing said toggle in tripping direction at least when said contacts are closed, and a current-responsive trip device operable to cause operation of said toggle upon the occurrence of an overload, said spring means being operable by the operating mechanism upon opening of the contacts to reset the toggle and to permit resetting of parts of said trip device.

5. In a circuit breaker, relatively movable contacts, a switch member movable to open and to close said contacts, actuating mechanism for moving said switch member to open and to closed circuit positions, a trip mechanism including a linkage biased to cause an opening operation of the contacts, a latch for latching the trip mechanism in operative position, and a current-responsive trip device operable to unlatch the trip mechanism upon the occurrence of an overload, said switch member acting through said linkage when said member is moved to open the contacts to effect resetting of the trip mechanism.

6. In a circuit breaker, relatively movable contacts, actuating mechanism for said contacts, a contact arm operable to open the contacts, a trip member operable to cause said mechanism to open said contacts, a linkage including a spring for operating the trip member, means for releasably restraining said linkage and a current-responsive trip device for releasing the linkage upon the occurrence of an overload current, said spring being operable by the contact arm upon opening of the contacts to effect resetting of the linkage.

7. In a circuit breaker, relatively movable contacts, operating mechanism for said contacts, a contact arm operable to open the contacts, a trip member, a toggle operatively connected to said trip member, a resilient linkage connecting the toggle to the contact arm, said resilient linkage biasing the toggle in a direction to operate the trip member at least when said contacts are closed, a current-responsive trip device operable in response to predetermined circuit conditions to cause operation of the trip member, said resilient linkage being operable by the contact arm when said arm is operated to open the contacts to reset the trip member and permit resetting of the trip device.

8. In a circuit breaker, relatively movable contacts, operating mechanism for said contacts, a contact arm operable to open the contacts, a trip member operable to cause opening of the contacts, a toggle operatively connected to said trip member, a resilient linkage connecting the toggle to the contact arm, said linkage biasing the trip member in tripping direction at least when said contacts are closed, and a trip device responsive to overload circuit conditions to cause operation of the resilient linkage, said linkage being operable by the contact arm upon opening of the contacts to reset the toggle and trip member.

9. In a circuit breaker, relatively movable contacts, operating mechanism for said contacts, a trip member operable to cause opening of the contacts, a releasable linkage biasing the trip member in tripping direction at least when said contacts are closed, means for releasably restraining said linkage, and an electroresponsive trip device responsive to overload current to release said linkage, said linkage being operable by the operating mechanism upon opening of the

contacts to reset the trip member and permit resetting of the electroresponsive trip device.

10. In a circuit breaker, relatively movable contacts, operating mechanism for said contacts, a trip member operable to cause said mechanism to open the contacts, a linkage comprising a member connected to the operating mechanism, a reciprocable member cooperating with said member and connected to said trip member, and resilient means between the member and said reciprocable member, said linkage being operable to cause operation of the trip member, current-responsive trip means responsive to overload currents to cause said linkage to operate the trip member, said linkage being operable by the operating mechanism when the contacts are opened to reset the trip member.

11. In a circuit breaker, relatively movable contacts, a switch member movable to open and to close said contacts, operating mechanism for said contacts, a trip member operable to cause opening of the contacts, a toggle operatively connected to the trip member, a linkage including a pair of cooperating members one of which is connected to the switch member the other being connected to the toggle, and a spring cooperating with said linkage, said spring biasing the trip member in tripping direction at least when said contacts are closed, a latch normally restraining the toggle to thereby restrain said trip member, and a current-responsive trip device operable in response to predetermined circuit conditions to cause said latch to release the toggle.

12. In a circuit breaker, relatively movable contacts, operating mechanism for said contacts including closing means for said contacts, means operatively relating said closing means to said movable contacts, releasable trip mechanism including a toggle independent of said relating means and operable to cause opening of the contacts, a resilient linkage biasing said toggle in tripping direction, a latch for releasably restraining said toggle, and a current-responsive trip device operable in response to predetermined circuit conditions to release the trip mechanism, said toggle being reset to operative position by opening of the contacts.

13. In a circuit breaker, relatively movable contacts, operating mechanism for said contacts, a trip mechanism including a toggle movable to cause opening of the contacts, latch means to releasably restrain the toggle, means connecting the toggle to a part movable with the operating mechanism, said connecting means including a spring operable when the toggle is released to move the toggle to thereby cause opening of the contacts, a current-responsive trip device operable to cause release of the toggle, said connecting means being operable by the operating mechanism when the contacts are opened to restore the toggle to latching position.

14. In a circuit breaker, the combination of relatively movable contacts, operating mechanism for said contacts, a pivoted trip member operable to cause opening of the contacts, a linkage comprising a pair of cooperating members one of said members being operatively related to the trip member and the other member being connected to the operating mechanism, and a spring associated with said cooperating members to bias the trip member in tripping direction at least when the contacts are closed, said spring acting

when released to operate the trip member, latch means to releasably restrain the linkage, and a current-responsive trip device to operate the latch and release the spring, said linkage being operable by the operating mechanism acting through the spring to reset the trip member.

15. In a circuit breaker, the combination of relatively movable contacts, operating mechanism for said contacts, a contact member operable to open the contacts, a trip member operable to cause opening of the contacts, a toggle operatively connected to the trip member, said toggle being biased in tripping direction, means for operatively connecting the toggle and the contact member, said connecting means comprising a member connected to the contact member, a member connected to the toggle, and a spring associated with said members, latch means for releasably restraining the toggle, and a current-responsive trip device operable in response to overload circuit conditions to release the toggle, said connecting means acting to transmit the movement of the contact members when the contacts are opened to reset the toggle.

25. 16. A circuit breaker comprising relatively movable contacts, operating mechanism for said contacts, means comprising a resilient linkage including a compression spring connected to a part movable with the movable contact, said spring being compressed when said contacts are closed and being operable to cause an operation of the operating mechanism to open said contacts, means for releasably holding said spring in compressed condition, and current responsive means operable in response to predetermined overload conditions in the circuit for causing said holding means to permit operation of said linkage, the movement of said contacts to open position acting through said linkage to reset said holding means to holding position.

30. 17. A circuit breaker comprising relatively movable contacts, a member movable in accordance with the movement of said contacts, operating mechanism for said contacts, tripping means including a toggle, a spring connecting said member to said toggle and stressed when said contacts are closed, said toggle being operable to cause said operating mechanism to open said contacts, means for holding said spring in stressed condition, and a trip device operable in response to overload currents in the circuit to cause said holding means to permit the spring to operate said toggle, said movable member acting when the contacts open to reset the toggle.

35. 18. A circuit breaker comprising relatively movable contacts, operating mechanism for said contacts, a switch member operable to open the contacts, a trip member operable to cause opening of the contacts, a resilient linkage connecting the switch member to said trip member, said resilient linkage biasing the trip member in tripping direction at least when the contacts are closed and acting when released to operate the trip member, latch means for releasably restraining the trip member, and a current-responsive trip device operable in response to overload circuit conditions to release the trip member, said resilient linkage being moved by the opening movement of said switch member to reset the trip member.
